CLAIM

The ornamental design for a set of instruments and tools for laboratories as shown and described.

DESCRIPTION

1. Set of instruments and tools for laboratories

1.1 : Front view

1.2: Back view

1.3: Right side view

1.4: Perspective view

1.5: Partial front view

1.6: Another partial front view

1.7: Partial back view

1 Claim, 7 Drawing Sheets
